THERMOSTATIC CARBURETOR CHOKE
DEVICEKnight N. Willmore and Arch P. Carroll, Fairfax,
and Carl O. Stucker, Ponca City, Okla.Application September 26, 1931
Serial No. 565,368

4 Claims. (Cl. 123—119)

This invention relates to an improved apparatus for choking or fuelizing an internal combustion engine or motor, and has for its object the production of a simple and efficient 5 means for automatically controlling the choke after the starting of the engine without the necessity of manually actuating a choke valve.

Another object of this invention is the production of a simple and efficient choking device 10 for an internal combustion motor, which is applicable to automobiles, trucks, busses, motor-boats, etc., and one of the primary objects of this invention is the production of a simple and efficient thermostatically controlled valve 15 mounted in communication with the exhaust manifold or exhaust pipe of the engine whereby the heat passing through the exhaust pipe or exhaust manifold will automatically actuate the choke valve to automatically open the choke 20 valve at the predetermined temperature.

Other objects and advantages of the present invention will appear throughout the following specification and claims.

In the drawing:—

25 Figure 1 is a side elevation of an explosive engine showing the carburetor and means cooperating with the exhaust manifold for actuating the choke valve.

Figure 2 is an enlarged sectional view taken 30 on line 2—2 of Figure 1.

Figure 3 is a sectional view taken on line 3—3 of Figure 2.

By referring to the drawing it will be seen that 1 designates the internal combustion engine or any suitable or desired type having an 35 exhaust manifold pipe 2 and an exhaust discharge pipe 3. Secured to and communicating with the exhaust manifold pipe 2 is a thermostatically controlled valve containing casing 3, 40 within which casing 3 is mounted a thermostatically controlled butterfly valve 4, as clearly shown in Figure 2 and 3 of the drawing.

This butterfly valve 4 is connected at one end to a spiral tapering coil 5, which spiral tapering 45 coil 5 is preferably formed of a plurality of coils of sheet metal having a high coefficient of expansion. The end of the tapering thermostatic coil 5 is hingedly secured in any suitable or desired manner as at 6 to one side of the thermostatically controlled butterfly valve 4. This 50 thermostatic tapering coil 5 is carried upon a journal pin 7, which journal pin 7 is carried by the thermostatic coil supporting frame 8. This frame 8 comprises a pair of parallel side 55 arms 9, which are secured at their extremity by

means of suitable fastening screws 12 to the sides of the casing 3, as clearly shown in Figures 2 and 3 of the drawing.

The opposite ends of the arms 9 are connected by means of a circular head 11, which 60 is provided with a centrally located aperture 12. This frame 8 constitutes an efficient support for the thermostatic coil spring 5 and the aperture 11 will permit the passage of the exhaust gases freely through the casing 3 without obstruction. 65 The casing 3 is provided with a flexible tube of any suitable or desired structure indicated by the numeral 13 which in turn is connected at its discharge end to the exhaust discharge pipe 3'. 70

As shown in Figure 1 the carburetor 14 is connected to the intake manifold 15 of the engine 1 and this carburetor 14 carries a choke valve 16 of the usual type, which choke valve 16 is actuated by means of an actuating arm 75 17 secured thereto and extending upon the outer face of the carburetor 14 as is usual with such type of operating arm. This choke valve operating arm 17 is connected to an operating link 18, which link also is connected to an operating 80 arm 19 carried by the supporting shaft 20 of the thermostatically controlled butterfly valve 4.

The operation of the device is as follows:—

As soon as the engine is started, heat will 85 naturally pass through the exhaust manifold pipe 2 through the medium of the exhaust gases passing from the cylinders of the engine and the heat will then pass into the casing 3 and longitudinally thereof, and out through the discharge pipe 13 into the exhaust discharge pipe 3'. The heat from the exhaust gases will cause the thermostatic coil spring 5 to expand, and as the heat increases and the coil spring 5 continues to expand or lengthen, the valve 4 will be 90 forced to a closed position in the direction of the arrows shown in Figure 3, thereby moving the choke valve to a fully opened position and the heat control valve will remain closed, thereby protecting the thermostatic element against 95 excessive heat. When the engine is turned off, and the exhaust gases no longer pass through the exhaust manifold 2, the thermostatic coil spring 5 will retract and again open the thermostatically controlled butterfly valve 4 and 100 close the choke valve 16 or move the same to the position shown in Figure 1. When the engine is stopped, the parts naturally return to their 105 respective positions occupied at the start in the length of time proportionate to the temperature 110

of the air and the consequent temperature of the engine.

From the foregoing description it will be seen that a very simple and efficient means has been produced for properly fuelizing or choking the engine at all times and for automatically controlling the opening and closing of the choke valve. Through the medium of the connecting link 18 the choke valve 15 will be opened and closed proportionately in their respective movements to the butterfly valve 4. This action will cause a proper and gradual control of the fuel passing from the carburetor into the engine.

It should be understood that certain detail changes in mechanical construction may be employed without departing from the spirit of the invention, so long as these changes fall within the scope of the appended claims.

What is claimed as new is:

1. In combination with an explosion engine provided with an exhaust manifold and an exhaust discharge pipe communicating therewith, a carburetor having a choke valve, a casing communicating with said exhaust manifold and also communicating with said exhaust discharge pipe, a thermostatically controlled valve mounted within said casing, an operating arm carried by said thermostatically controlled valve, and a link connecting said arm with said choke valve for automatically opening and closing said choke valve as said thermostatically controlled valve is actuated within said casing.

2. A choke control device for an internal combustion engine comprising a casing adapted to be secured to the manifold of an engine, said casing provided with a means for connecting to the exhaust pipe of a manifold of an engine, a butterfly valve mounted within said casing, a thermostatic coil spring mounted within said

40

casing and engaging said butterfly valve for closing said butterfly valve as said coil spring expands, and an arm connected to said butterfly valve and adapted to be engaged with the choke valve of a carburetor for opening the choke valve of a carburetor when said butterfly in said casing is closed. 80

3. A device of the class described comprising a casing, a butterfly valve journaled in one end of said casing, a frame mounted within said casing, a thermostatic tapering coil spring anchored upon said frame and engaging one end of said butterfly valve, whereby said butterfly valve will be forced to a closed position as said tapering thermostatic spring expands, and an arm carried by said butterfly valve and adapted to be secured to a choke valve of the carburetor of an engine for opening the choke valve as said butterfly valve is moved to a closed position. 85

4. A device of the class described comprising a casing adapted to communicate with an exhaust manifold of an engine, a butterfly valve mounted therein for swinging movement, a thermostat supporting frame secured to the inner face of said casing and comprising a plurality of parallel arms, means for anchoring one end of said arms to said casing, a head connecting the other ends of said arms and being provided with a centrally located aperture to permit the passage of exhaust gases to said casing unobstructed, a discharge pipe connected to said casing and adapted to communicate with the discharge pipe of an exhaust manifold, and an operating arm connected to said butterfly valve and adapted to cooperate the choke valve of the carburetor for 100 opening and closing the same. 105
